UNITED STATES PATENT OFFICE.

WALTER C. HARLOW, OF BROOKLYN, NEW YORK.

BUILT-UP ARTICLE.

939,833.

Specification of Letters Patent.

Patented Nov. 9, 1909.

Application filed December 24, 1907. Serial No. 407,969.

To all whom it may concern:

Be it known that I, WALTER C. HARLOW, a citizen of the United States of America, and a resident of Brooklyn, in the county of 5 Kings and State of New York, have invented certain new and useful Improvements in Built-Up Articles, of which the following is a specification.

This invention relates to built up articles 10 whose surface portions are composed of sectional shells, all or partly of metal, and to the method of making the same.

The object is to cheapen and simplify the manufacture of metal-surfaced objects, to 15 permit the employment of metal so thin as ordinarily not to be self-supporting or not sufficiently shock-resisting, and to do away with the usual soldering, bolting, flanging, or spinning-over processes usually employed 20 for uniting mechanically the several elements of the surface. To these ends the articles constructed according to this invention have their surface regions formed of thin, sectional, dis-united shells, and are 25 provided with heavy internal bodies of hardened plastic material, which serve as a key for holding the several sections assembled in their proper relative positions. It will thus be seen that the composite body serves as a 30 support and reinforce for the sectional metal surface; and the invention is therefore sharply defined from that class of constructions in which concrete or cement articles are 35 reinforced internally by metal.

My invention is applicable to the manufacture of a great variety of articles composed, at least in part, of metal, such as lamp bases, telephone bases, pendent and bracket light fixtures, ink-stands, urns, vases, and 40 other receptacles, and the like.

In the accompanying drawings are shown several illustrative examples of the invention.

Figure 1 is a vertical longitudinal section 45 through a pendent light fixture constructed after my invention; Fig. 2, is a like view of a bracket light fixture; Fig. 3 is a like view of a base adapted to carry a desk telephone or a portable electric light; Fig. 4 is a like view 50 of an ornamental pitcher or vase; and Fig. 5 is a like view of a base and font for an oil lamp.

Referring to Fig. 1, the numerals 1, 2, 3, 4, 5, 6 and 7, indicate the several thin sectional shells of metal composing the surface portion of the pendent fixture, the number

and shape of these sections being governed by considerations of convenience and the effect which it is desired to create. 8 indicates lateral tubes or conduits projecting 60 through section 4, and 9 is a globe which may be carried by section 7. It will be seen that the several sectional shells are dis-united, that is they are not directly connected one with another. A is the hollow 65 body of hardened plastic, which supports the surface shells, and also the members 8, and holds all of these in their proper relative positions.

In Fig. 2, 11, 12, 13 and 14 are the sec- 70 tional metallic shells, and A the supporting body as before. 15 is an internally threaded bushing held in the base of the body, and 16 is a pipe screwed therein.

Fig. 3 shows metallic shells 17, 18, and 19, 75 together with a threaded nipple 20, which may be held in the upper end of the hollow body A, of hardened plastic.

In Fig. 4 are found the sectional shells 21, 22, 23, and 24, supported by the body A 80 of hardened plastic. This view shows how one of the metallic shells may be replaced by a glass or porcelain one, shell 22 being of vitreous or similar material. 25 is a handle which may be bolted to section 21. 85

Fig. 5 shows a structure analogous to that of Fig. 4, 26, 27 and 28 being metallic shells, and 29 a shell of glass or porcelain. The section 26 may have an internally-threaded thimble 30 secured therein. 31 is the metal 90 lining of the oil font.

Referring to these several views, it will be seen that the body A, in each instance, serves in the nature of a key, locking the dis-united shells in assembled position. 95

In making devices such as illustrated, the superficial metal portions are stamped or drawn in presses. They are then assembled in suitable molds, which if necessary, may be split or made in sections for easy removal 100 from the assembled articles. These molds receive likewise any other portions of the assembled articles, which portions it is desired to unite in an integral structure with the metal portions. Examples of such parts are 105 the metal tubes 8, in Fig. 1, which carry electric lamps at their ends; the tube 14, Fig. 2, which may also be regarded as one of the surface shells, carrying a lamp or cluster of lamps at its end, also the internally threaded bushing 15; the nipple 20, Fig. 3, on which an electric lamp socket may 110

be screwed; and the glass or porcelain shells 22 and 29 of Figs. 4 and 5.

When all the parts have been properly located, I pour in a suitable plastic compound 5 which hardens on setting. I prefer for this purpose a substance which expands very slightly on setting, instead of shrinking like ordinary cement. A high degree of tenacity is also desirable. An example of a plastic 10 composition which I may use is one made by taking substantially equal parts by weight of oxid of magnesia and crystallized chlorid of magnesia, adding water to form a paste, and stirring in suitable inert material, such 15 as crushed stone or sand. Naturally, however, I am not limited to this formula. If necessary, I employ means to tamp the filling compound, in order to exclude air and obtain a maximum strength. If the article 20 is to be hollow, I introduce either a removable core or a hollow form, preferably of papier mâché, which may be cheaply manufactured, and which has sufficient stiffness

to resist the pressure of the composition during the tamping. If necessary, the cores 25 may be made in sections. When the shells have been properly filled, the molds are set aside until the filling hardens, after which the molds are removed, leaving the article 30 completely unified, without any of the usual mechanical means.

What I claim as new is:

A built-up, composite article consisting of sectional, metal shells too thin for structural strength, and a substantial body of cementitious material self-hardened in contact with and adhering to said metal shells and supporting and holding together said shells to constitute a metal jacket or surface. 35

Signed at New York city this 11th day of 40 December 1907.

WALTER C. HARLOW.
